ATTORNEY.

UNITED STATES PATENT OFFICE.

JOHN CLANCY, OF KENNER, LOUISIANA.

RAIL-JOINT.

1,329,227.

Specification of Letters Patent. Patented Jan. 27, 1920.

Application filed October 6, 1919. Serial No. 328,688.

To all whom it may concern:

Be it known that I, JOHN CLANCY, a citizen of the United States, residing at Kenner, in the parish of Jefferson and State of Louisiana, have invented new and useful Improvements in Rail-Joints, of which the following is a specification.

This invention relates to rail joints and has particular application to the connecting bars, which are designed to accommodate the fastening bolts in a manner to prevent bending or loosening of the bolts and nuts, and to also eliminate undue expansion between the meeting ends of the rails.

10 To this end, the connecting bars are provided upon their inner confronting faces with longitudinally disposed ribs through which the fastening bolt is passed the ribs unitedly reinforcing the bolt to prevent bending of the latter, while each of the connecting bars is also provided upon its opposite face with a longitudinal groove to receive the head of the bolt to prevent turning of the latter when subjected to vibration.

15 The nature and advantages of the invention will be better understood when the following detail description is taken in connection with the accompanying drawings, the invention residing in the construction, combination and arrangement of parts as claimed.

20 In the drawing forming part of this specification like numerals of reference indicate similar parts in the several views and wherein:

25 Figure 1 is a side elevation of the rail joint showing my improved connecting bars.

Fig. 2 is a transverse sectional view taken through one of the fastening elements.

30 Fig. 3 is a perspective view of one of the connecting bars.

Referring to the drawing in detail, 10 and 11 indicate respectively the meeting ends of the rail which may be joined together in any suitable manner, the particular construction of rail forming no part of the invention. Arranged at the opposite side of the rail are the connecting bars 12 which are designed to receive or accommodate the fastening elements or bolts 13 to prevent bending or loosening of the latter. For this purpose each of the connecting bars 12 is provided with a longitudinally extended rib 14 upon the inner side or face of the bar to lie against the web of the rail when

the bar is in position. Manifestly, the ribs 14 of the respective bars are arranged in horizontal alinement when the bars are arranged at opposite sides of the rail, and the ribs provided at suitably spaced intervals 60 with alined openings 16 adapted to register with the opening in the webs of the rail for the reception of the fastening bolts 13. The combined width of the ribs 14 and the web of the rail provide a reinforcement for the 65 bolt which prevents bending of the latter and also minimizes the expansion of the rails between the meeting ends thereof. Each of the bars 12 is also provided upon its outer side with a longitudinally extended 70 groove 17, the groove being shaped to receive the square head 13' of the fastening element 13. With the head 13' positioned within the groove, turning of the bolt is obviated when subjected to vibration. It will be noted 75 from an inspection of Fig. 1 that the bolts are passed through the rail and bars 12 so that the heads of the bolt will be alternately disposed at opposite sides of the rail. A nut 19 is associated with each fastening bolt, 80 while a washer 20 is also fitted upon the bolt and may if desired be in the form of a nut lock to prevent retrograde movement of the nut.

85 While I have shown and described what I consider the preferred embodiment of the invention, I desire to have it understood that I do not limit myself in this connection in that such changes may be resorted to when desired as fall within the scope of 90 what is claimed.

Having thus described my invention what I claim as new is:

95 The combination with the meeting ends of the rail, of connecting bars arranged at opposite sides of the rail, each bar having longitudinally extending ribs upon the inner face thereof and a longitudinally extended groove upon the outer face thereof, fastening bolts passed through said bars and 100 through the alined ribs thereof, and said grooves adapted to receive the heads of the fastening elements to prevent turning of the bolts, nuts secured to the opposite free ends 105 of the bolts and the said ribs coöoperating with the web of the rail to prevent bending of the bolt.

In testimony whereof I affix my signature.

JOHN CLANCY.
